US00D435013S

United States Patent [19]

Clowers et al.

[11] Patent Number: Des. 435,013

[45] Date of Patent: ** Dec. 12, 2000

[54] POWER TOOL BATTERY PACK

[75] Inventors: **Earl R. Clowers**, Anderson, S.C.;
Mark A. Etter; **Michael A. Lagaly**,
both of Jackson, Tenn.

[73] Assignee: **Porter-Cable Corporation**, Jackson,
Tenn.

[**] Term: **14 Years**

[21] Appl. No.: **29/105,752**

[22] Filed: **Jun. 1, 1999**

[51] LOC (7) Cl. **13-02**

[52] U.S. Cl. **D13/103**

[58] Field of Search D13/103, 119;
429/96-100, 159, 163, 174

[57] CLAIM

The ornamental design for a power tool battery pack, as
shown and described.

DESCRIPTION

FIG. 1 is a front and top right perspective view of a power

tool battery pack with a first voltage capacity;

FIG. 2 is a front elevational view of the power tool battery
pack shown in FIG. 1.

FIG. 3 is a rear elevational view of the power tool battery
pack shown in FIG. 1.

FIG. 4 is a right side elevational view of the power tool
battery pack shown in FIG. 1.

FIG. 5 is a left side elevational view of the power tool
battery pack shown in FIG. 1.

FIG. 6 is a top plan view of the power tool battery pack
shown in FIG. 1.

FIG. 7 is a bottom plan view of the power tool battery pack
shown in FIG. 1.

FIG. 8 is a front and top right perspective view of a power
tool battery pack with a second voltage capacity.

FIG. 9 is a front elevational view of the power tool battery
pack shown in FIG. 8.

FIG. 10 is a rear elevational view of the power tool battery
pack shown in FIG. 8.

FIG. 11 is a right side elevational view of the power tool
battery pack shown in FIG. 8.

FIG. 12 is a left side elevational view of the power tool
battery pack shown in FIG. 8.

FIG. 13 is a top plan view of the power tool battery pack
shown in FIG. 8.

FIG. 14 is a bottom plan view of the power tool battery pack
shown in FIG. 8.

FIG. 15 is a front and top right perspective view of a power
tool battery pack with a third voltage capacity.

FIG. 16 is a front elevational view of the power tool battery
pack shown in FIG. 15.

FIG. 17 is a rear elevational view of the power tool battery
pack shown in FIG. 15.

FIG. 18 is a right side elevational view of the power tool
battery pack shown in FIG. 15.

FIG. 19 is a left side elevational view of the power tool
battery pack shown in FIG. 15.

FIG. 20 is a top plan view of the power tool battery pack
shown in FIG. 15; and,

FIG. 21 is a bottom plan view of the power tool battery pack
shown in FIG. 15.
